2 FIG. 1.

FIG. 2.

FIG. 3.

FIG. 4.

Joseph C. Dunham

REISSUED
AS NO. 15574
APR 10 1933

UNITED STATES PATENT OFFICE.

JOSEPH C. DUNHAM, OF OKLAHOMA, OKLAHOMA.

WEATHER STRIP.

1,416,698.

Specification of Letters Patent. Patented May 23, 1922.

Application filed July 12, 1920. Serial No. 395,537.

To all whom it may concern:

Be it known that I, JOSEPH C. DUNHAM, a citizen of the United States, and a resident of Oklahoma city, in the county of 5 Oklahoma and State of Oklahoma, have invented certain Improvements in Weather Strips, of which the following is a specification, reference being had to the accompanying drawings.

10 This invention relates to weather strips of that general character in which a resilient sheet metal strip is employed and adapted to be interposed between the edge of the door and the jamb and adapted to be tensioned by 15 the closing of the door.

The object of the invention is to provide means to prevent passage of air between a door and jamb.

Referring to the accompanying drawings, 20 in which:—

Figure 1 is an elevation view of a door and door frame on which the improved weather-strip is installed.

Figure 2 is an enlarged sectional view 25 taken on the line 2—2 of Figure 1.

Figure 3 is a reproduction of a portion of Figure 2, but with the door slightly open.

Figure 4 is a reproduction of the same 30 portion of Figure 2, with the door a little further open.

Figure 5 is a perspective view of a small portion of the improved weather-strip.

In Figures 2 to 4 the weather-strip is 35 shaded in solid black and is shown of exaggerated thickness.

Like characters of reference designate like parts in all the figures.

The door and frame shown in this instance include the outer casing 10, the jamb 11, 40 the inner casing 12, and the door 13; the jamb being rabbeted as at 14 to receive the door.

The improved weather-strip 15, hereinafter referred to as the strip, is of sheet metal, for 45 example sheet brass of good spring quality.

In cross-section, that portion of the strip between the lines A—A and B—B (Figure

5) is shaped as an arc of a circle and adapted to have its edges bear against the edge 16 of the door 13; the round back surface of 50 the strip resting against the jamb 11 in the rabbet 14.

The remaining portion of the cross-section of the strip between the lines B—B and C—C is also shaped as an arc of a circle, 55 with a portion 17 adapted to be fastened to the jamb 11 by nails 18.

The centers of curvature of both the curved sections of the strip are both on the same side of the strip. It will be noted that 60 one curve ends at one edge in a peak 19, while the meeting ends of both curves also end in a common peak 20.

In closing the door 13, the strip 15, held at its outer edge by the nails 18, is wholly 65 or partially straightened out in cross-section, thereby placing said strip under tension and forming it into a packing between the door and jamb.

The improved strip may be used between 70 the meeting-rails of two sashes, or in any place where the surfaces of two relatively movable parts meet each other with a sliding contact or movement.

Spring brass eight-thousandths of an inch 75 thick is found to be suitable for the strip.

The following is claimed:—

A compound-curved sheet metal weather strip formed in cross section into two arc-shaped portions the edges of one of which 80 are adapted to bear against the edge of a door with the curved back of said portion bearing against the jamb in the rabbet thereof, the other portion being provided with an end portion for fastening to the 85 jamb, the centers of curvatures of both arc-shaped portions being on the same side of the strip and the peaks of both curves engageable with the edge of a door to be placed under tension at separated points. 90

Witness my hand this 23 day of March, 1920.

JOSEPH C. DUNHAM.
